United States Patent Office

Des. 219,718
Patented Jan. 12, 1971

219,718

TYPEWRITER

Richard H. Penney, New York, N.Y., assignor to Sperry Rand Corporation

Filed Mar. 30, 1970, Ser. No. 22,118

Term of patent 14 years

Int. Cl. D18—01

U.S. Cl. D64—11

FIG. 1.

FIG. 2

FIG. 3

FIG. 4.

FIG. 5.

FIG. 1 is a front perspective view of a typewriter showing the new design;

FIG. 2 is a left side elevational view thereof, the right side being similar in appearance;

FIG. 3 is a top view;

FIG. 4 is a front elevational view; and

FIG. 5 is a rear elevational view.

I claim:

The ornamental design for a typewriter, substantially as shown and described.
